ANTENNA

Charles R. Fleming, Los Angeles, Calif.

Application September 15, 1944, Serial No. 554,218

6 Claims. (Cl. 250—33)

This invention relates to antennas for receiving or transmitting radio waves.

The object of the present invention is to provide an antenna for short wave and broadcast frequency bands which increases the signal strength delivered to a receiver. Another object is to provide a simple and compact antenna for installation indoors on or near a receiver or outdoors on a support. Still another object is to provide an antenna which has improved selectivity, and which decreases the static and other extraneous wave-lengths which may interfere with desired reception.

These and other objects are attained by my invention which will be understood from the following description and the accompanying drawing in which Fig. 1 is a side elevational view showing my device, the insulating jacket of the preferred form being removed to better show the construction; Fig. 2 is an elevational view partly in section, taken at right angles to Fig. 1, with the insulating jacket in place; Fig. 3 is a side elevational view of the insulating jacket; Fig. 4 is a cross-sectional view taken on the line 4—4 of Fig. 1; Fig. 5 is an end view of the insulating jacket; Fig. 6 is an enlarged cross-sectional view of a portion of the jacket taken on the line 6—6 of Fig. 5.

My device consists of an outer V-shaped wire or rod 11, and an inner V-shaped wire or rod 12, disposed in the same vertical plane, with the center portions of each brought together and twisted in two or three turns forming the twisted portion 13, the wires or rods in this portion each being electrically insulated as shown, the outer V insulation being indicated as black and the inner V as green. The outer prongs 11a and 11b are longer than the inner prongs 12a and 12b, and I have found that this feature is important in giving optimum signal strength on reception. Eyelets are formed at the ends of the prongs, not only to prevent damage, or injury to persons, but also for supporting means when the device is hung on the wall or case of the receiver. The outer prongs 11a and 11b are preferably spaced at about 60° angle apart, and the inner prongs 12a and 12b are spaced symmetrically between the outer prongs with about 30° angle between them. I have found that this arrangement gives maximum improvement in the strength of a received radio signal.

The wires or rods forming my device are preferably of the usual circular cross-section, and of about 6 gauge or heavier, to give rigidity and strength when the center portions are twisted to-

gether to form the assembly as shown. For the usual broadcast range, the outer prongs 11a and 11b are made about 17 inches long, and the inner prongs 12a and 12b are made about 14 inches long.

The center portions of the outer and inner V's, when twisted, provide the center loops 15 and 16, to which are attached insulated lead wires 17 and 18, for connection to the terminals of the receiver or transmitter. The outer V is connected to the ground terminal, and the inner V to the aerial terminal.

For convenience in handling and protection, and in certain methods of mounting, I provide 15 an insulating jacket 19, preferably of wood or plastic, which is provided with a threaded coupling 20 in its lower end, this coupling having inside threads 21 adapted for threaded attachment to a pipe, for convenience in fastening to 20 an outdoor pipe mounting. The coupling is provided with a slot 23 at its inner end so that it may be screwed into the jacket; and an opening 22 through which the lead wires 17 and 18 may project. The jacket 19 is adapted to slip over 25 the twisted portion of the V's, and to then be sealed in place by means of a plastic putty 24 or the like, or in other ways fastened on the twisted portion. A separator 25 is provided between the loops 15 and 16.

30 The twisted center portions of the V's not only holds the parts together, but gives good mechanical strength to the device, and is also believed to act as a wave trap or filter to remove unwanted static and other disturbing electrical waves.

35 My device is convenient for attachment to a cabinet radio receiver as an indoor antenna, and has greatly improved reception of weak and long distance signals, both in the broadcast and in the short wave bands. It may also be advantageously used with outdoor mountings.

40 While I have described my invention by illustrative examples, I do not wish to be restricted to the particular details given, but limit my invention only insofar as required by the prior art 45 and the spirit of the appended claims.

I claim:

1. A four-pronged antenna comprising two rods forming outer and inner V-shaped members, respectively, with two outer and two inner prongs, 50 the center portion of each member being electrically insulated and twisted together to form a rigid assembly, the four prongs being disposed in a single plane.
2. A four-pronged antenna comprising two rods forming outer and inner V-shaped mem-

bers, respectively, with two outer and two inner prongs, the center portion of each member being electrically insulated and twisted together to form a rigid assembly, the four prongs being disposed in a single plane, and an insulating jacket adapted to fit over the twisted portion of the rods, and lead-in wires extending from the end of said jacket opposite the four prongs and electrically connected to said center portions.

3. The device of claim 2, together with threaded pipe-connecting means in said jacket adapted

for mounting the antenna on a pipe support through which run said lead wires.

4. The device of claim 1, the said prongs being provided at their ends with mounting eyelets.

5. The device of claim 1 in which the outer prongs are longer than the inner prongs.

6. The device of claim 1, in which the outer prongs are positioned at about 30 degrees from the vertical and the inner prongs are about 15 degrees from the vertical.

CHARLES R. FLEMING.
